[57] **CLAIM**

The ornamental design for vehicle wheel face, as shown and
described.

DESCRIPTION

FIG. 1 is a front elevation of the vehicle wheel face having
our new ornamental design;

FIG. 2 is an enlarged fragmentary view thereof; and,

FIG. 3 is a front perspective view of the wheel in FIG. 1.
That which is illustrated in broken lines forms no part of the
claimed design and is shown merely for purposes of illus-
tration of the environment of the claimed design.
